UNITED STATES PATENT OFFICE.

OSCAR E. BRACONIER, OF ROCKFORD, ILLINOIS.

IRONING-MACHINE.

SPECIFICATION forming part of Letters Patent No. 619,703, dated February 14, 1899.

Application filed September 28, 1898. Serial No. 692,073. (No model.)

To all whom it may concern:

Be it known that I, OSCAR E. BRACONIER, a citizen of the United States, residing at Rockford, in the county of Winnebago and State 5 of Illinois, have invented certain new and useful Improvements in Ironing-Machines, of which the following is a specification.

The object of this invention is the production of an ironing-machine simple and cheap 10 enough in its construction to be adaptable to household use, for which purpose it is primarily intended.

In the accompanying drawings, Figure 1 is a side elevation of the ironing-machine. Fig. 15 2 is a longitudinal central section of the same. Fig. 3 is an end elevation, partly in section, of the mechanism. Fig. 4 is a view of the driving-gears and sprocket-wheels for the ironing-rollers, and Fig. 5 is a transverse central section through the ironing-rollers and the apron for feeding the fabric between them.

Like letters of reference indicate corresponding parts throughout the several views.

A is the supporting-frame. A' is the base 25 thereof.

A² are the lower journal-bearings in the supporting-frame.

A³ are the upper bearing-openings in the supporting-frame.

30 B is a shaft mounted in the lower journal-bearings A² and is capable of a slight rocking movement therein.

B' are arms fixed with relation to the shaft B, having the journal-bearings B² at their free 35 ends.

B³ is the lower ironing-roller, having trunnions B⁴ for the journal-bearings B².

B⁵ is a gear-wheel fixed to one of the trunnions B⁴. This gear-wheel meshes with the 40 spur-gear B⁶, which latter, rigidly secured to the sprocket-wheel B⁷, revolves loosely upon the shaft B.

B⁸ is an arm or lever fixed on the rock-shaft 45 B, intended to oscillate the latter and to permit a yielding movement of the roller B³, with relation to the other ironing-roller. By this arrangement of gearing for the lower roller B³ the movement of the roller to and from the upper ironing-roller C does not alter or affect the mesh of its driving-gears, they remaining in the same relative position 50 regardless of this movement.

C is the upper ironing-roller.

C' are the hollow bearing-studs at each end of the roller C. C² is a sprocket-wheel fixed 55 on one of said bearing-studs.

C³ is a stud providing a journal for one end of the roller C. C⁴ is a hollow shaft which acts as the journal for the opposite end of the roller C and also permits the introduction of 60 gas to the roller C for heating the same.

D is the inner tube of the gas-burner for heating the roller C. It is fixed with relation to the hollow shaft C⁴ and is perforated along its lower side to permit the escape of the gas 65 to the outer tube of the burner. D' is the said outer tube, perforated along its upper side, at which perforations the gas is discharged to the flame.

E is a gasoline-gas generator of usual form. 70

E' is the pipe leading from a gasoline-storage receptacle to the generator E, and E² is a supporting-arm for said generator and pipe.

It will thus be seen that while the upper ironing-roller C is fixed in its position in the 75 supporting-frame A the lower ironing-roller has a yielding movement to permit different thicknesses of fabric to be passed between the peripheries of the two ironing-rollers.

F is an expansion spiral spring located under the outer and free end of the lever B⁸, the tendency of which spring by raising the said lever and thereby rocking the shaft B is to throw the lower roller B³ into contact with the periphery of the upper ironing-roller C. 80 The tension of the spring F is regulated by the hand-screw F'.

F² is a cam-lever by means of which the lower roller B³ may be withdrawn and held from contact with the upper roller C. When 90 the cam-lever F² is raised or released, the lower roller B³ is thrown into contact with the upper ironing-roller C by the force of the spiral spring F.

G is a movable carrier-apron for feeding 95 the fabric to be ironed between the ironing-rollers. It has a contact with the lower ironing-roller B³ at both upper and lower points in the periphery of the roller. The lower ironing-roller B³ is journaled slightly forward 100 from the upper roller C, whereby the apron G is held in contact with a considerable portion of the periphery of the heated roller C and is driven by the roller B³. The apron

travels over and is supported at either end by the idler-rollers G', one of which (the one at the rear of the machine) is capable of an adjustment by means of the screw and sliding bearing-block G² for changes in the length of the apron.

H is the driving-shaft, operated by foot or other power. H' is a sprocket-wheel fixed thereon.

10 H² is a counter-shaft having three sprocket-wheels H³, H⁴, and H⁵ fixed thereon.

H⁶ is an endless chain belt running over the sprocket-wheels H' and H³. H⁷ and H⁸ are also endless chain belts running from the 15 sprocket-wheels H⁴ and H⁵, respectively, and over the sprocket-wheels B' and C', respectively, driving the lower and the upper ironing-rollers.

By the gearing provided for the lower roller 20 its speed is made considerably slower than that of the upper roller, it being in practice about one to three, respectively.

In operation the gasolene-generator is started in the usual manner and the gas produced 25 ignited at the heating-burner, which extends nearly the full length of and within the upper ironing-roller C. Of course illuminating-gas may be used for heating this roller when such gas is convenient. When the heating-flame 30 is burning, the machinery may be started and goods to be ironed laid on the carrier-apron G. The proper degree of pressure to be applied to the goods while passing through the ironing-rolls is obtained by adjusting the tension 35 of the spring F by means of the hand-screw F'. The proper tension of the carrier-apron G is obtained by means of the screw adjustment G² at each side of the apron.

It will be noticed that any movement of 40 the lower ironing-roller B' toward or from the upper ironing-roller C does not disturb the relation of the former with the carrier-apron G; but, on the contrary, the said apron is constantly driven by the said roller and an 45 even tension maintained regardless of the movement of the roller.

The greater speed imparted to the upper ironing-roller C by the form of gearing shown causes the said roller to polish the 50 surface of the fabric being ironed, imparting a smooth finished appearance thereto.

I claim as my invention—

1. In an ironing-machine, in combination, a supporting-frame, an ironing-roller rotatably 55 mounted thereon, a rock-shaft also mounted on the frame, arms on the rock-shaft, an ironing-roller journaled between the said arms, a lever for moving the rock-shaft, a car-

rier-apron extending around the last-mentioned roller, two supporting-rollers for the 60 carrier-apron, means for heating one of said ironing-rollers and means for driving the heated ironing-roller at a greater speed of rotation than the other ironing-roller, substantially as and for the purpose specified. 65

2. In an ironing-machine, in combination, a supporting-frame, an ironing-roller rotatably mounted on the frame, a heating-burner for said ironing-roller, a rock-shaft also mounted on the frame, arms on the rock-shaft, an ironing-roller journaled between the said arms, a lever for moving the rock-shaft, a carrier-apron extending around the last-mentioned roller, two supporting-rollers for the carrier-apron, means for adjusting one of said last- 70 mentioned rollers and means for driving the heated ironing-roller at a greater speed of rotation than the other ironing-roller, substantially as and for the purpose specified. 75

3. In an ironing-machine, in combination, a supporting-frame, an ironing-roller rotatably mounted on the frame and having a hollow shaft-bearing at one of its ends, a gas-burner within the said ironing-roller, a rock-shaft also mounted on the frame, arms on the rock-shaft, an ironing-roller journaled between the said arms, a lever fixed to the rock-shaft, a spring for the lever, a cam hand-lever engaging the first-mentioned lever, a carrier-apron extending around the last-mentioned 85 roller, two supporting-rollers for the carrier-apron, means for adjusting one of said rollers, a driving-shaft and means for imparting motion to the two said ironing-rollers whereby the heated roller is caused to rotate at a 90 greater speed than the other ironing-roller, substantially as and for the purpose specified. 95

4. In an ironing-machine, in combination, a supporting-frame, an ironing-roller rotatably 100 mounted on the frame, a rock-shaft also mounted on the frame, arms on the rock-shaft, an ironing-roller journaled between the said arms, a pivoted lever for moving the rock-shaft, a spring for said lever, means for 105 heating one of said rollers, means for rotating both of said rollers at different rates of speed, an endless carrier-apron passing over one of said rollers, two idler-rollers for supporting said endless carrier-apron, and means 110 for adjusting the tension of the carrier-apron, substantially as and for the purpose specified.

OSCAR E. BRACONIER.
